UNITED STATES PATENT OFFICE.

ARON RAUCH, OF NEW YORK, N. Y.

WEAVING-FRAME FOR HAIR-GOODS.

1,154,338.

Specification of Letters Patent. Patented Sept. 21, 1915.

Application filed September 13, 1913. Serial No. 789,588.

To all whom it may concern:

Be it known that I, ARON RAUCH, a citizen of the United States, and residing at New York, in the county of New York and State 5 of New York, have invented certain new and useful Improvements in Weaving-Frames for Hair Goods, of which the following is a specification, such as will enable those skilled in the art to which it appertains to make 10 and use the same.

The object of my present invention is to provide a weaving frame for use in connection with human hair and which is adapted for use by hair dressers and others, a further 15 object being to provide a weaving frame of the class described which can be readily adjusted for varying conditions of use, and can be easily applied to a table, stand, or other convenient support.

20 A still further object of this invention is to provide a frame for weaving hair in connection with which thread carried on ordinary spools can be employed, and by which hair goods of any desired length may be 25 woven, this being made possible by providing a revoluble head or extension on one frame member, and also by reason of a construction which permits the user to take up or adjust the several threads to keep the 30 same of uniform tension.

To these ends, and to such others as the invention may pertain, the same consists, further, in a novel construction, combination, and adaptation of the parts, as will be 35 hereinafter more fully described and then specifically defined in the appended claim.

40 I clearly illustrate my invention in the accompanying drawings which form a part of this specification, and in which drawings similar letters of reference indicate like parts throughout the several views, in which;—

45 Figure 1 is a side elevation partly in section showing my improved hair weaving frame in operative position, and Fig. 2 is an enlarged section of a detail of the construction.

50 In the practice of my invention, I provide a suitable support 1 such as a stand or table on which is secured, in an upright position, a spool frame member 2 the securing means being shown as an angle plate 3 and bolt 4 which passes upwardly through the support 1 and through one arm of the angle plate 55 and is provided with a nut 5, the other arm of the angle plate being secured to the spool

frame 2 by screws 6 or other fastening devices.

The frame member 2 is provided with a plurality of horizontal bores or apertures 7 60 adapted to receive backwardly ranging pin-bolts 8 having rounded heads 9 and threaded ends 10 on which are carried wing nuts 11 and above each of these pin-bolts is an open guide loop 12, the purpose of which will be 65 hereinafter described. A pin cushion 13 of any suitable shape or construction may be provided at the top of the frame member 2 for the use of the operator.

In order to enable the operator to weave 70 hair goods of unusual length, I provide an adjustable frame member 14 having at the bottom thereof an angle plate 14' fixed thereto and the free arm of which is adapted to rest on the support 1 and be adjustably secured thereto in any desired manner, as by the clamp 15, and the upper part 75 of the frame member 14 is provided with a guide and retaining device consisting, in the form of construction shown, of an eye-screw 16, and said frame member 14 is further provided with a revoluble head sleeve or extension 17 having an attaching device consisting, in the form of construction 80 shown, of an eye-screw 18. The head sleeve 17 is loosely mounted on a vertical pin or bolt 19 secured in the frame member 14, and a thimble 20 may be carried on the upper part of the pin or bolt 19 for the use 85 of the operator, and the frame member 14 90 is further provided with pins 21 on which surplus spools 22 may be supported.

In the operation of weaving hair goods of unusual length on my improved frame, I 95 mount a plurality of ordinary spools 23 on the pin bolts 8 and pass the threads 24 thereof through the guide loops 12 and over to the adjusting frame 14 and connect the ends of said threads with the loop or eye 18 100 on the head sleeve 17 as shown in dotted lines. The head sleeve 17 is then preferably turned one or more times to wind said threads thereon after which an intermediate portion of said threads is hooked over the shank of the loop or eye 18 and then carried 105 down and passed beneath the loop or eye 16 as shown in the drawing. The spools 23 are then turned backwardly to tighten up on the threads 24 and when a uniform tension is obtained on all the threads 24 the wing nuts 11 110 are fastened down on the ends of the spools and the frame is ready for the weav-

- ing to begin. The above operation of connecting the threads with the head sleeve 17 and passing said threads under the loop or eye 16 locks said sleeve against rotation, 5 and after the operator has filled the space between the frame members, the wing nuts 11 are loosened and the threads are detached from the loop or eye 16 and the head sleeve 17 is turned so as to wind said threads and 10 the woven product thereon, after which the said threads are again passed over the loop or eye 18 and again down and around the shank of the loop or eye 16, after which the threads between the frame members are 15 again tightened by operating the spools 23 as hereinbefore described and the process of weaving is continued.

When it is desired to weave only a short length, the threads 24 are passed directly 20 to the loop or eye 16 and secured thereto, or therein after which the weaving operation is performed, as will be readily understood.

It will be understood that my improved weaving frame is adapted for effective use 25 in all work and under all conditions in which a frame of this class can be employed, and I do not desire to be understood as limiting myself to the detail features and construction and arrangement of parts as herein shown and described, as it is manifest that 30 variations and modifications therein may be resorted to, in the adaptation of my invention to varying conditions of use, without

departing from the spirit of my invention and improvements. I, therefore, reserve the 35 right to all such variations and modifications, as properly fall within the scope of my invention, and the terms of the following claim.

Having fully described my invention what 40 I claim as new and desire to secure by Letters Patent is:—

In a weaving apparatus of the class described, a vertical frame member the top of which is provided with a vertical loosely 45 mounted, rotatable head sleeve having a thread attaching device connected therewith, said frame member being also provided below said head sleeve with a thread guide and attaching device, and said head sleeve being 50 held against rotation by securing the threads to the thread attaching device connected with said head sleeve, turning said sleeve to wind the threads thereon and passing said threads over the attaching device on said 55 sleeve and under the guide and attaching device below said sleeve.

In testimony that I claim the foregoing as my invention I have signed my name in presence of the subscribing witnesses this 60 12th day of September, 1913.

ARON RAUCH.
